UNITED STATES PATENT OFFICE.

JOSEPH PHELPS, OF NORTH CALDWELL, NEW JERSEY, ASSIGNOR TO REMINGTON TYPEWRITER COMPANY, OF ILION, NEW YORK, A CORPORATION OF NEW YORK.

TYPEWRITING MACHINE.

Application filed June 11, 1923. Serial No. 644,571.

To all whom it may concern:

Be it known that I, JOSEPH PHELPS, citizen of the United States, and resident of North Caldwell, in the county of Essex and 5 State of New Jersey, have invented certain new and useful Improvements in Typewriting Machines, of which the following is a specification.

My invention relates to noise reducing 10 mechanism for typewriting machines and its chief object is to provide connections between the carriage motor or spring drum and the driving shaft of the ribbon mechanism which connections reduce noise to a minimum and do away entirely with the 15 clicking sound which is inherent in pawl and ratchet mechanism such as has heretofore usually been employed to connect the ribbon feeding mechanism with the carriage 20 spring drum.

To the above and other ends which will hereinafter appear, my invention consists in the features of construction, combinations of devices and arrangements of parts 25 hereinafter described and particularly pointed out in the claims.

In carrying out my invention in the present instance I introduce between the spring drum and the beveled driving pinion which 30 is concentric with it, a coiled spring so arranged as to provide a clutch connection between said pinion and said spring drum when the latter is turning to move the carriage in letter feeding direction, said coiled spring releasing so as automatically to disconnect the pinion from the drum when the latter turns oppositely during return movements of the carriage. The spring clutch is closely wound so as promptly to 35 bind on and clutch the beveled pinion and through it the ribbon feeding devices, thus avoiding lost motion which would be harmful, as a plurality of type impressions might otherwise be made at the same point 40 through the ribbon, tending to wear a hole in it. However, this close winding of the clutch spring might sometimes result in failure to release the pinion promptly during the carriage return movements, and in 45 order to insure such prompt release, I preferably employ a second coiled spring clutch oppositely wound from the first and which is introduced between the said pinion and its bearing. This second clutch acts to bind 50 or clutch the pinion to its bearing as soon 55 as the return movement begins, thus preventing friction or other accidental impulses from causing a back feeding of the ribbon.

My invention will be more particularly 60 described in connection with the accompanying drawings wherein—

Figure 1 is a fragmentary front elevation partly in section showing a carriage with its motor or spring drum having my 65 invention applied thereto.

Figure 2 is a vertical sectional view taken on a plane indicated by the section line 1 in Fig. 1 and looking in the direction of the arrow at said line. 70

Figure 3 is a general perspective view showing the novel parts or devices comprised in the clutch mechanism, said devices being separated or spaced apart for the sake of clearness. 75

The main frame of the machine comprises a top plate 1 on which are secured a pair of oppositely grooved guide rails, the rear rail only being shown herein and numbered 2. The guide rails co-operate through rollers 80 3 with the platen carriage of the machine as it travels back and forth across the top plate. The carriage may be the usual platen carriage of the Remington typewriting machine comprising a truck and a platen frame 85 shiftably supported on the truck, of which the grooved rear bar 4 and one of the end bars 5 are illustrated. Fixed to the right-hand rear corner of the carriage truck by a screw 6 is a curved arm 7 terminating in a hook in which is connected one end of a band or strap 8, the band running over the circular flange 9 of a spring drum 10 to which drum the end of the band 8 is connected at 11. The drum 9, 10 is vertically 90 arranged and projects upward through a slot indicated at 1^a in the top plate 1. During traveling movements of the carriage and turning movements of the drum the band 8 winds on and off the flange 9. The drum is 95 rotatively supported on a stub shaft 12 which in turn bears rotatively in a U-shaped bracket 13 secured by screws 14 to the underside of the top plate. The shaft extends 100 horizontally forward from its bearing and comprises a middle portion 12^a and a reduced forward portion 12^b, the portion 12^a providing a bearing for a flanged thimble-like part 15 which is fixed to the drum and serves as a hub therefor. To the shaft 12 110

is secured a hook 16 which is engaged by the inner end of a coiled main spring 17, the outer end of the main spring being secured at 18 to the spring drum 10. A cover plate 19 protects the main spring at the back. The shaft 12 is secured adjustably in its bracket or support by devices preferably like those disclosed in my co-pending application, Sr. No. 573,526, said devices including a knurled thumb piece 20 by which the position of the shaft may be adjusted and the tension of the main spring regulated. During movements of the carriage and back and forth rotary movements of the spring drum the shaft 12 remains stationary. The carriage main spring or motor spring as will be plain from Fig. 1 tends constantly to turn leftward or counter-clockwise, the force being transmitted to the drum 10 and from it through the band 8 to the platen carriage, movement of the carriage being normally controlled by the escapement devices (not shown). Not only does the spring drum or motor move the carriage leftward but it also feeds the ribbon and to this end there are provided a pair of intermeshing beveled pinions 21, 22, the pinion 21 being mounted concentrically with the spring drum in a novel manner presently to be described and the pinion 22 being mounted on the ribbon driving shaft 23 which is arranged transversely of the machine and is adapted to be slid endwise back and forth to reverse the direction of the ribbon feed as is well understood. Said shaft and the pinion 22 slidably engage so that the constant engagement between said pinion 22 and the pinion 21 is not disturbed by the endwise sliding movements of the shaft. The rotary driven member or pinion 21 is so connected with the rotary driving member, driver or spring drum that as the latter turns leftward it will turn the pinion, said pinion transmitting its turning movements to the pinion 22 and to the ribbon shaft 23, the return movement of the spring drum or driving member automatically breaking the connection with the driven member or pinion 21 so that the ribbon feed is inoperative during such return movements. The pinion 21 is bored out or perforated as indicated at 24, leaving, however, a slight flange or rib 25 at the front end of the bore. The outer face of the pinion back of its beveled teeth 26 is formed with a circular seat or depression 27 providing a sort of hub or binding face. The pinion 21 fits over a cylindrical member 28 which has two connecting bores 29 and 30, the bore 29 fitting over the part 12^a of the shaft 12 and the bore 30 fitting over the part 12^b of said shaft. A pin 31 on the shaft fits in a hole 32 in the member 28 so that said member is forced to turn with the shaft. At its outer or front end 65 the member 28 is formed with a depression

33 which is engaged by the flange 25 of the pinion 21 serving as a bearing for said pinion and assisting to maintain the bore 24 separated from the outer face of the bearing member 28. A headed screw 34 is threaded into the reduced end 12^b of the shaft, the head of said screw preventing displacement both of the member 28 and the pinion 21. Fitting closely or snugly over the seat or hub 27 is a coiled wire spring or clutch member 35. One end of said spring is free but the opposite end 35^a is turned outward, passing through an opening in an annular housing 36 which surrounds and encloses the clutch spring 35. The housing in addition to its annular portion 36 comprises ears 37 which are perforated to receive screws 38 by which the housing is secured to the front face of the drum 10. One of the ears in lieu of receiving a screw however is split as indicated at 39 to permit the annular part 36 to be readily contracted or expanded. The construction is such that when the spring drum turns towards the left it will act through the housing 36 on the outer end 35^a of the spring 35 to cause it to bind or clutch the pinion 21, forcing the pinion to turn with the drum; but when reversed as the carriage is restored from left to right, said drum acts through the housing 36 and end 35^a of the spring to release the pinion 21 from the clutch.

In order to insure complete freedom of the pinion at this time, I prefer to employ a second clutch member. This second clutch member is in the form of a flat coiled spring 40 which surrounds the member 28, being arranged in the space between said member and the bore 24 of the pinion 21. Said spring 40 fits closely over the member 28 and its front end is bent outward as indicated at 40^a to engage in a fore-and-aft groove 41 in the pinion 21, thus connecting the flat clutch spring 40 with the pinion. The pinion as it turns to feed the ribbon acts on the end 40^a to loosen the clutch 40 and render it inoperative; while when the reverse movement of the drum takes place, any tendency through binding or sticking of the main clutch 35 to turn the pinion 21 is prevented by reason of the spring clutch 40 gripping the outer face of the member 28.

It will be observed that when the spring drum turns leftward to advance the carriage and feed the ribbon the hub 15 turns with it as does the housing or annulus 36, the latter tightening the spring 35 on the hub portion of the beveled pinion 21 and forcing said pinion to turn with the spring drum. This action of the pinion loosens the inner clutch spring 40 which will rotate with the pinion 21, said spring 40 turning on the bearing member 28 which remains stationary as does the shaft 12 with which said member 28 is rigidly connected by the

pin and slot connection 31, 32. During return movements of the carriage, however, and consequently reverse turning of the spring drum, the main clutch spring 35 will 5 be loosened, releasing the pinion 21, and any tendency of said pinion to turn, due to accidental impulses of friction or the like, will be instantly transmitted to the clutch spring 40 which will bind on the periphery of the 10 co-operating clutch member 28, said member remaining stationary as before. The clutch devices are comparatively noiseless in operation and no sound results during carriage return movements due to interaction 15 of the connections between the carriage motor and the ribbon mechanism.

Principles of my invention are applicable to other parts of typewriting machines, and constructional changes may be made without departing from my invention.

What I claim as new and desire to secure by Letters Patent, is:—

1. In a typewriting machine, the combination of a rotary carriage motor, a rotary driven member having a hub, and a coiled spring clutch connected at one end to said motor and surrounding said hub, said spring clutch binding on said hub during rotary movements of said motor in one direction and releasing said hub and said driven member during rotary movements of said motor in the opposite direction.

2. In a typewriting machine, the combination of a rotary carriage motor, a ribbon driving pinion provided with a hub, and a clutch spring closely coiled about said hub and having one end connected to said carriage motor, said clutch spring binding on said hub during rotation of said motor in one direction only.

3. In a typewriting machine, the combination of a carriage, a carriage spring drum connected thereto, a ribbon driving pinion provided with a hub, a clutch spring coiled around said hub and having one end connected to said spring drum and the other end being free on the hub, said clutch spring binding on said hub when the spring drum turns to advance the carriage in letter-feeding direction, said spring releasing said hub during turning movements of said spring drum in the opposite direction.

4. In a typewriting machine, the combination of a rotary driver, a rotary driven member, a clutch spring coiled about said driven member, and a housing secured to said driver and closely surrounding said clutch spring, said housing having a slotted portion so that it may be readily expanded and contracted.

5. In a typewriting machine, the combination of a carriage, a spring drum connected thereto, a ribbon driving shaft, connec-

tions between said shaft and said spring drum comprising a pair of intermeshing beveled pinions, one of said pinions being provided with a hub, and a wire spring coiled around said hub and binding thereon during rotary movements of said hub as the carriage travels in printing direction and thus serving to connect the pinion with the spring drum, said spring automatically releasing said hub and said pinion during the return movements of said spring drum and said carriage.

6. In a typewriting machine, the combination of a rotary carriage motor, a rotary driven member, a relatively stationary bearing therefor, a releasable clutch between said motor and said driven member, and a second releasable clutch between said driven member and its bearing.

7. In a typewriting machine, the combination of a driving member, a driven member, a support for said driven member, and a pair of oppositely acting clutches one between the driving and driven members and the other between the driven member and its support.

8. In a typewriting machine, the combination of a rotary driving member, a rotary driven member, a stationary bearing, and a pair of oppositely wound spring clutches, one connecting the driving and driven members and the other between the driven member and the bearing.

9. In a typewriting machine, the combination of a driving member, a rotary driven member provided with a perforation, a clutch spring surrounding said hub portion exteriorly and connecting said driven member with said driving member, and a second clutch spring arranged inside said perforation and adapted to act oppositely from said first recited clutch spring.

10. In a typewriting machine, the combination of a carriage, a carriage motor, a driven member, and a pair of spring clutches, one of said clutches being connected to the other through said driven member.

11. In a typewriting machine, the combination of a carriage, a carriage spring drum, a coiled spring clutch having one end connected to said drum, a driven member on which said clutch operates, and means for preventing said driven member from moving when released by said clutch.

Signed at the borough of Manhattan, city of New York, in the county of New York and State of New York, this 8th day of June, A. D. 1923.

JOSEPH PHELPS.
